HEAD SCARF OR THE LIKE

Carol B. Sullivan, New York, N. Y.

Application March 30, 1955, Serial No. 35,287

Term of patent 7 years

(Cl. D3—13)

Fig. 1 is a top perspective view of a head scarf, showing my new design; and

Fig. 2 is a side perspective view thereof as it appears in wearing position.

I claim:

The ornamental design for a head scarf or the like, as shown.
